UNITED STATES PATENT OFFICE

MORTON J. ADELSON, OF LARCHMONT, NEW YORK

ADVERTISING BAND

Application filed October 27, 1932. Serial No. 639,921.

This invention relates to advertising labels, and has for an object to provide a label of this type in the form of a band adapted to be applied to an article of merchandise, and with means for holding another article of merchandise.

The invention provides a band having a suitable space or panel for receiving descriptive matter, such as advertising matter indicative of the article of merchandise to which it is applied and the name of the manufacturer or seller thereof, and with means for holding another article of merchandise in concealed position so that a purchaser receives a second useful article when purchasing the article of merchandise to which the band is attached.

Still another object of the invention is the provision of a device of this character formed of a single piece of material to provide a rectangular body portion having side and end extensions or flaps which are foldable rearwardly in superposed position with relation to the central portion, the end flaps when in folded relation forming a pocket with the body portion for holding an article of merchandise, the side flaps when in folded relation being adapted to be connected to form a band with the central portion by which the same may be attached about an article of merchandise.

Still other objects reside in the novel features of construction and arrangement of parts which will be more fully described and claimed hereinafter.

The invention is illustrated in the accompanying drawing, in which

Figure 1 is a top plan view of the band applied to an article of merchandise, such as a necktie;

Fig. 2 is a plan view of the under side of the band, showing the means for securing the ends of the band together;

Fig. 3 is a vertical sectional view on the line 3—3 of Fig. 2;

Fig. 4 is a cross sectional view on the line 4—4 of Fig. 2;

Fig. 5 is a plan view of the band in open arrangement with an article of merchandise, such as a strip of safety matches, secured thereto.

For the purpose of illustrating the invention, the band 10 is shown in the drawing applied to a necktie 11, but it is to be understood that the same may be applied to any suitable article of merchandise, such, for instance, as a pair of stockings, without departing from the spirit of the invention.

The band 10 has a strip of safety matches 12 secured thereto, which is illustrative of the article of merchandise which the purchaser receives with the band when purchasing the article to which the band is applied. Instead of a strip of safety matches, however, said band may contain collar buttons or golf tees, or any other article of merchandise which may be conveniently attached to or enclosed within the band.

Preferably the band 10 is made of a single piece of flexible material, such as thin cardboard, or the like. As shown in Fig. 5, the said band comprises a rectangular body portion 13, which is provided with side extensions or flaps 14 and 15 and end extensions or flaps 16 and 17.

The end extensions or flaps 16 and 17 are foldable rearwardly in superposed position with relation to the body portion 13, on the horizontal fold lines 18 and 19, respectively, thereby forming with the said body portion 13 a portion or container for holding an article of merchandise, such as the strip of safety matches 12, which may be secured to the said body portion 13 by any desired means, such as staples 20. The flap 17 is provided with a slit 21, in which the tapered end of the flap 16 is inserted for holding the said flaps in folded relation covering the safety matches 12.

The side extensions or flaps 14 and 15 are

likewise foldable rearwardly one upon the other on the vertical fold lines 22 and 23, respectively, overlying the end flaps 16 and 17. These side flaps form the ends of the band 5 which are adapted to be interconnected to complete the endless formation of the band. For this purpose the extension or flap 14 is notched at 24, providing a shoulder 25 by which the end of the flap 14 may be inserted 10 in the arcuate slot 26 of the flap 15 and the flaps secured in folded relation as shown in Fig. 2.

The said horizontal and vertical fold lines on which the said flaps are foldable, as hereinbefore described, define the rectangular body portion 13, the front face of which constitutes a panel for descriptive matter, such as advertising matter indicative of the article of merchandise to which the band is to be applied and the name of the manufacturer or seller thereof, as shown in Fig. 1. The vertical fold lines 22 and 23 are preferably perforated or weakened lines which will tear readily when the purchaser desires to remove 25 the band from the article of merchandise to which it is applied, and when so removed the band provides a second useful article enclosed in the band as a container when purchasing the article to which the band is applied.

30 It is to be understood that when the band is applied to an article of merchandise, such as the necktie 11, the said end extensions are in folded or in closed relation, thus forming with the body portion a closed container in 35 which an article of merchandise may be arranged without the necessity of securing it in position therein and which cannot be removed therefrom without removing the band from the necktie.

40 What I claim is:

1. An advertising device for an article of merchandise, comprising a body portion, a pair of flaps connected to said body portion, said flaps being foldable to overlie the said body portion, and a second pair of flaps secured to said body portion, said second pair of flaps being foldable to overlie the first pair of flaps and being provided with interlocking means for locking said flaps together which interlocking means requires distorting of one of the said flaps to permit separation thereof when in locked engagement, thereby forming a band with the body portion by which the same may be attached about an article of merchandise, and said pairs of flaps forming with the body portion a container adapted to hold another article of merchandise.
2. An advertising band for an article of merchandise, formed of a single piece of material, comprising a panel portion, a pair of folded extensions, and a second pair of folded extensions, said extensions when in folded relation overlying the panel portion, said second pair of extensions being provided with

interlocking means for locking the same together to complete the formation of the band with the said panel portion for attaching the band about an article of merchandise, and said pairs of extensions forming with the 70 said panel portion a closed compartment adapted to completely house another article of merchandise, the said second pair of extensions being folded on weakened lines which may be readily torn to remove the 75 band from the first-mentioned article of merchandise.

3. A merchandising label provided with means for attaching it to an article of merchandise and also having means independent 80 of the attaching means for receiving another article of merchandise wholly contained within said label, said first-mentioned means including a pair of flaps provided with weakened lines which may be readily torn to remove the label from the first-mentioned article of merchandise.
